VACUUM CLEANER

Gustaf Einar Lofgren, Riverside, Conn., assignor
to Electrolux Corporation, Dover, Del., a cor-
poration of Delaware

Application April 23, 1936, Serial No. 75,954

16 Claims. (Cl. 230—133)

My invention relates to vacuum cleaners and more particularly to improved means for exhausting air from a vacuum cleaner unit.

A vacuum cleaner of the type herein contemplated includes a casing adapted to be supported in substantially horizontal position on a horizontal surface. A flexible air conduit or hose is provided for connecting the casing, which contains a dust separating member and a fan, with a cleaning tool. During normal operation of the device, air is drawn in through the cleaning tool and the conduit, is passed through the dust separating member for the removal of entrained dust and is discharged in purified state into the atmosphere. In order to reduce the back pressure as far as possible, it is desirable to provide an exhaust opening or openings having as large a cross-section as possible. It is also desirable that the exhaust opening or openings deliver the air in a direction away from the surface on which the cleaner unit is supported in order that this air will not agitate any dust which may be on the surface.

At times it may be wished to use the cleaner unit as a blower and to connect the air conduit or hose to an exhaust opening so that the air may be readily delivered to a desired point of use.

In accordance with my invention, there is provided a vacuum cleaner unit having a plurality of exhaust openings. One of these openings is arranged for the connection therewith of an air conduit. Valve means are provided operable upon the connecting of the hose to automatically cut off flow of air through the remaining exhaust openings. The exhaust openings to which the hose is connectible is preferably arranged in a substantially horizontal plane in order that when the hose is connected it may extend from the cleaner in a substantially horizontal direction, and air vanes are provided for directing the air upwardly and away from the supporting surface when the air conduit is not connected. These vanes are advantageously formed as a part of the aforesaid valve means and are displaceable along with the valve means when the hose is connected. The remaining exhaust openings are preferably located in a part of the casing which is so curved that the air discharged therethrough is directed away from the supporting surface.

Another object of my invention is to provide a filtering member advantageously arranged in conjunction with the plurality of exhaust openings so that all of the air exhausted from the cleaner unit must pass through the filter. My invention also contemplates locating the exhaust

openings and the aforesaid valve means in an end-piece which may be removably secured to the main portion of the cleaner casing by means of a member which is accessible for manipulation through one of the exhaust openings. Preferably this means includes a bolt disposed within the exhaust opening to which the air conduit may be connected and extending flush with the outer surface of the air vanes carried by the valve means. This bolt may be made accessible for manipulation by displacing the vanes and valve means in a manner similar to that in which they are displaced when the hose is connected. Further, my invention contemplates arranging the aforesaid filter member so that the fastening of the end-piece to the main housing secures it in place.

Further objects and advantages of my invention will be apparent from the following description considered in connection with the accompanying drawings, which form a part of the specification and of which:

Fig. 1 is a side-view, partially in cross-section, of a vacuum cleaner unit including one embodiment of my invention;

Fig. 2 is a rear view on a somewhat reduced scale of the device shown in Fig. 1;

Fig. 3 is a cross-sectional view on an enlarged scale and is taken on the lines 3—3 of Figs. 1 and 2;

Fig. 4 is a cross-sectional view on an enlarged scale taken on the line 4—4 of Fig. 2;

Fig. 5 is a cross-sectional view taken on the line 5—5 of Fig. 4;

Fig. 6 is a cross-sectional view of a portion of the device illustrated in Fig. 4 but with an air conduit connected thereto;

Fig. 7 is a cross-sectional view taken on the line 7—7 of Fig. 6;

Fig. 8 is a cross-sectional view similar to Fig. 4 but showing another embodiment of my invention;

Fig. 9 is a cross-sectional view taken on the line 9—9 of Fig. 8;

Fig. 10 is a cross-sectional view taken on the line 10—10 of Fig. 8;

Fig. 11 is a cross-sectional view of a portion of the device shown in Fig. 8 but with an air conduit connected thereto;

Fig. 12 is a cross-sectional view similar to Fig. 8, but showing a third embodiment of my invention;

Fig. 13 is a cross-sectional view of a fourth embodiment of my invention;

Fig. 14 is a cross-sectional view taken on the line 14—14 of Fig. 13; and

Fig. 15 is a cross-sectional view taken on the line 15—15 of Fig. 13.

5 Referring more particularly to the device shown in Figs. 1 through 7, reference character 10 designates generally a casing of a vacuum cleaner unit. Casing 10 includes the main casing member 11 which may preferably comprise sheet metal stampings forming a hollow elongated body more or less open at each end. One end of member 11 may be closed by means of a front cover 12 which may be removably secured to member 11 by any suitable means. Cover 12 is provided with an opening 13 adapted to receive a coupling member 14 secured to one end of a flexible hose or air conduit 15. The other end of hose 15 may be connected with a suction nozzle 16 by means of a hollow rigid handle member 17.

10 A dust separating member 20 in the form of a bag having its open mouth secured to a flanged ring 21 is disposed within casing member 11. The flange of ring 21 is adapted to be clamped between the casing member 11 and the front cover 12 when the latter is secured in place. Dust separating member 20 is made of suitable material such as cloth which is pervious with respect to air, but impervious with respect to dust.

15 A pair of spaced bulkheads 22 and 23 are disposed within casing member 11 and divide the interior thereof into a dust bag compartment 24, a motor-fan compartment 25, and a filter compartment 26. A motor fan unit, including an electric motor 27 and a centrifugal fan 28 mounted within an air-tight casing 29, is disposed within motor-fan compartment 25 and is supported between bulkheads 22 and 23 by air-tight sealing rings 30 and 31 which engage within openings formed in the respective bulkheads and in the opposite ends of casing 29.

20 Filter space 26 is bounded in part by a portion of casing member 11 and in part by an end-piece 34, which may be in the form of a casting. In the embodiment shown in Figs. 1 through 7, casting 34 is secured to the main casing member 11 by means of screws 35. Casting 34 is formed with a cylindrical exhaust opening 36 having a substantially horizontal axis, and with a plurality of slot-like exhaust openings 37. Openings 37 are located in the rounded upper part of casting 34 so that the air discharged therethrough will be directed away from the surface on which the device is supported.

25 From the foregoing, it will be seen that the casing of the vacuum cleaner unit includes the main casing member 11, the front cover 12, and the end-piece 34, and that both the front cover and the end-piece form a portion of the exterior of the casing.

30 Secured within opening 36 in casing 34 is a cylindrical member 38, which, if desired, may be made of metal or "Bakelite". Member 38 is provided with a cylindrical bore 39 of uniform diameter and with one or more grooves 40 extending from the inner end of the member to an intermediate point thereof. Cylindrical member 38 is provided with one or more ports 41 towards its inner end, and a valve member 42 is reciprocally mounted within bore 39. Valve member 42 is provided with projections 43 which engage within grooves 40 to prevent rotation of the valve member. The valve member 42 is further provided with a plurality of air deflecting vanes 44 across the outer end. A conical spring 45 is disposed between the valve mem-

ber and a ring 46 clamped between the end of member 38 and a partition 47, the spring tending to hold the valve member in the position shown in Figs. 1, 3 and 4.

5 Partition 47 is secured to casting 34 and includes a substantially horizontal wall 48 and a substantially vertical wall 49 which serve to partition off a space 50 from the rest of the filter compartment 26. Exhaust openings 37 and ports 41 communicate with this space 50. Wall 49 10 is formed with a circular opening 51 communicating with the interior of member 38.

15 A plate 53 is carried by bulkhead 23 and is formed with an outer circular flange 54. Reference character 55 designates generally a filter which includes a solid circular plate 56 and an annular plate 57. Plates 56 and 57 are held in spaced relationship by means of a perforated cylinder 58. Filter cloth 59 is disposed between plates 56 and 57. The central opening in annular plate 57 fits around a cylindrical projection 60 formed by wall 49, whereby the filter 55 is positioned between wall 49 and plate 53.

20 The operation of the above described device is as follows:

25 With the hose 15 connected to front cover 12, as shown in Fig. 1, the device is in condition for cleaning. Rotation of fan 28 by means of motor 27 causes air to be drawn in through nozzle 16, handle 17, hose 15, and coupling 14 to the interior of dust bag 20. Here any entrained dust is deposited, and the air passes through the material of the dust bag and through the central opening in bulkhead 22 to the fan. Air discharged from the fan passes through and around the motor 27 and through the opening in bulkhead 23 to the filter compartment. Here the air flows in the direction indicated by the arrows, which is radially outward around the edge of plate 53 and thence inwardly through the filter cloth 59 and the perforated cylinder 58 to the interior of member 38. A portion of the air passes straight through member 38 to the atmosphere, being deflected upwardly as it leaves the member by vanes 44. The remainder of the air passes through ports 41 to space 50 and thence through openings 37 to the atmosphere. It will be noted that all of the air thus discharged is directed away from the supporting surface. Furthermore, the aggregate area of the openings 37 and the openings between vanes 44 is sufficiently great so that but a small back pressure is built up.

30 If it is desired to employ the device for blowing purposes, coupling 14 is removed from inlet opening 13 and is attached to the exhaust opening formed by member 38, as is shown in Fig. 6. When the coupling 14 is secured within member 38, the end of the coupling displaces valve member 41 to the left, as viewed in the figures, thereby compressing spring 45. In this position, the valve member covers the ports 41, thereby cutting off the flow of air through these ports to space 50 and hence, prevents exhaust of air through openings 37. Consequently, all 35 of the air is forced to pass into hose 15.

35 Spring 45, being under compression, tends to displace coupling 14 to the right, as viewed in Fig. 6, but the coupling is positively secured in member 38 by the balls 14a engaging an annular recess formed in the member. The construction of this coupling is described in detail in the co-pending application of Lars Ell, Serial No. 62,888, filed February 8, 1936, Patent No. 2,146,252, issued February 7, 1939, and is such that an axial 40

force in this direction does not tend to release the balls from the groove, but tends to wedge them more tightly therein.

If it is desired to clean or replace filter 55, screws 35 are removed, thus releasing casting 34 from the main casing member 11. This filter may then be removed through the opening which is normally closed by casting 34 and may be cleaned or replaced by a new one.

In the embodiment shown in Figs. 8 through 11, casting 34 is secured to the main casing member 11 by means of a single bolt 65. This bolt is rotatably mounted in an arm 66 which extends across the inner open end of cylindrical member 38 and is secured to the cylindrical member by means of screws 67. Bolt 65 is provided with spaced collars 68 and 69 which prevent longitudinal movement of the bolt with respect to arm 66 and hence, with respect to member 38 and casting 34. The inner end of bolt 65 is threaded, as is shown at 70, and is adapted to engage a threaded sleeve 71 secured to an arm 72 which is supported on member 73 forming a part of the seal 31 in the bulkhead 23. The other end of bolt 65 is provided with a preferably knurled head 74, the outer end of which is substantially flush with the outer edges of vanes 44. Spring 45 is disposed between valve member 42 and a washer 75 which surrounds bolt 65 and bears against arm 66. Plate 56 of filter 55 is formed with a small central opening within which sleeve 71 fits snugly. The plate bears against a sleeve 78 which surrounds sleeve 71 and is consequently of greater diameter than the opening in plate 56.

The operation of this embodiment is the same as that described in connection with Figs. 1 through 7 insofar as the flow of air is concerned. With the parts in the position shown in Fig. 8 air is exhausted through both the exhaust opening 37 and through the opening in the end of member 38 in the same manner as described in connection with Fig. 4. When the hose is connected within member 38, as is shown in Fig. 4, valve member 42 is moved to the left so as to cover ports 41 and the entire flow of air is through member 38 and into the hose in the same manner as described in connection with Fig. 6. The hose coupling shown in Fig. 11 is described in detail in my co-pending application, Serial No. 61,473, filed January 30, 1936, Patent No. 2,102,802, issued December 21, 1937, and includes catch member 14b which engages in an annular groove, thus positively resisting the force of spring 45.

When it is desired to remove the filter 55, valve member 42 is pressed inwardly by the fingers until knurled head 74 is exposed sufficiently to the grasp by the fingers. Thereupon, it is turned in the proper direction to unscrew bolt 65 from sleeve 71 and when this has been accomplished, casting 34 is released from the main part of the casing 11, and may be removed therefrom. Filter 55 may then be removed and cleaned or replaced by a new one and the casting secured in place again by screwing the end of bolt 65 into sleeve 71. As bolt 65 is tightened, it draws the edges of casting 34 against the edge of the opening formed in casing 11 and the parts are thus held together in substantially air-tight relationship. At the same time, the filter 55 is secured in place between wall 49 and sleeve 78 and the heads of bolts 79 which secure member 73 to bulkhead 23.

The embodiment shown in Fig. 12 differs from

that described in connection with Figs. 8 through 11 principally in the fact that sleeve 71 is extended to adjacent the inner end of member 38, wherefore bolt 65 may be that much shorter. Arm 66, in which bolt 65 is journaled, is formed with a cylindrical part 80 having a flared open end adapted to receive the end of sleeve 71. Bolt 65 is formed with a collar 69 disposed between arm 66 and washer 75. The force required to hold casting 34 to casing member 11 is exerted by the collar 69 against arm 66, while the only force between the collar and the washer 75 is that required to prevent the bolt dropping out when it is unscrewed from sleeve 71, and the force exerted by spring 45 against the washer is sufficient for this purpose.

The device shown in Fig. 12 has the advantage over that shown in Figs. 8 through 11, that it is somewhat easier to engage the threaded end of the shorter bolt with the sleeve 71 than it is to engage the threaded end of the longer bolt. The operation of the two devices is otherwise the same and the description thereof need not be repeated.

In the embodiment shown in Figs. 13 through 15, the bolt 65 for securing the end-piece 34 in place engages a threaded member 85 rigidly secured to a pivoted arm 86. This arm is rigidly secured, as by welding, to a member 87 having a cylindrical bore which receives a pin 88. Pin 88 is supported in a U-shaped member 89 which may be welded to the bottom of casing 11. Member 87 is formed with a recess 90 containing a spring pressed ball 91, which engages within a recess 92 formed in member 89 when the ball is brought into alignment with the recess. The length of arm 86 is less than one-half the width of casing 11 so that it may be pivoted to a substantially horizontal position, as is shown in dash and dot lines in Fig. 14.

The free end of arm 86 is formed with a recess adapted to receive a projection 93 formed on a disc 94. Projection 93 may be the head of a rivet which extends through the disc and secures thereto the central part of spring member 95. The ends of spring 95 are secured to a ring 96. Ring 96 is formed with a flange 97 which retains in place a ring 98, which is adapted to be received and supported within ring 31. A piece of filter cloth 99 is formed with a circular center opening and the edge of the cloth around this opening is clamped between rings 97 and 98. Filter cloth 99 has the shape shown in Fig. 13 and may consist of two pieces of cloth sewed together along the line 100. This cloth is retained between spring 95 and disc 94.

In this embodiment the cylindrical member 101, within which member 42 is mounted, is shown as a stamping, but it performs the same function as does member 38 in the preceding embodiments.

With the parts assembled as shown in Fig. 13, air discharged through the opening in bulkhead 23 is forced to pass through the filter 99. The air flow tends to distend the filter. The air after having passed through the filter enters member 101, and a portion of the air passes directly through between louvers 44. The remainder of the air passes through ports 41 and through outlet openings 37 formed in end-piece 34. As described in connection with the previous embodiments, when an air conduit is connected to member 101, member 42 is moved to the left so as to cut off flow through ports 41, and all of the air passes into the conduit.

End piece 34 may be removed from the main part of the casing 11, by unscrewing bolt 65. To do this, valve member 42 is forced inwardly so as to uncover the knurled head 74 on the bolt in order that it may be gripped with the fingers. When bolt 65 is released from the arm 86, the end piece is free to be removed.

If it is desired to renew the filter, arm 86 is pivoted in either direction to a horizontal position, spring 95 being deformed slightly so as to permit rivet 93 to be disengaged from the opening in the end of the arm. With the arm 86 out of the way, ring 98 may be removed from within ring 31 and the filter as a whole removed through the opening normally closed by end-piece 34. A new filter may then be inserted and the arm 86 pivoted to a vertical position, where it is retained by the engagement of the spring pressed ball 91 with the opening 92. In this position the arm engages rivet 93 and holds the filter in place and the screw threaded member 85 is in alignment with bolt 65 when the end-piece 34 is put in place, and the bolt may be readily engaged with member 85 to hold the end piece in position.

It will thus be seen that I have provided a vacuum cleaner unit having a plurality of exhaust openings available for the exhaust of air while the cleaner is being used for suction purposes and that means are provided for connecting a hose to one of these openings and at the same time cutting off flow of air through the remaining openings so that all of the air passes into the hose. Furthermore, all of the exhaust openings are so arranged that air discharged therethrough is directed upwardly and away from the supporting surface. In the embodiments shown in Figs. 8 through 15, a single member is provided for securing the end-piece, in which the exhaust openings are formed and which closes a filter chamber, to the remainder of the casing. This means is normally practically concealed from view and yet is readily accessible when it is desired to remove the end-piece.

While I have described several more or less specific embodiments of my invention, it is to be understood that this has been done for purposes of illustration only and that the scope is to be limited only by the appended claims viewed 50 in the light of the prior art.

What I claim is:

1. In a vacuum cleaner, a casing having an exhaust opening, an air conduit connectible to said opening, air deflecting means for guiding flow of air through said opening when said conduit is disconnected, said deflecting means being inwardly displaceable from a position substantially flush with the exterior of said casing by the connecting of said air conduit, and means for producing flow of air through said casing and said opening.

2. In a vacuum cleaner, a casing having an exhaust opening, an air conduit connectible to said opening, air deflecting means movably mounted in said opening for guiding flow of air through said opening when said conduit is disconnected, said deflecting means being inwardly displaceable from a position substantially flush with exterior of said casing by the connecting of said air conduit, resilient means resisting displacement of said deflecting means and forcing the latter against said conduit, and means for positively locking said conduit in said opening.

3. In a vacuum cleaner, a casing having an inlet opening and a plurality of exhaust openings,

means for producing flow of air through said casing, a hollow member secured at one end to said casing and extending inwardly from one of said exhaust openings, the other end of said hollow member being arranged to receive all of the air exhausted from said means, said hollow member being formed with a port communicating with the other of said exhaust openings, and a cylindrical member reciprocably mounted in said hollow member for selectively closing and opening said port.

4. In a vacuum cleaner, a casing having an inlet opening and a plurality of exhaust openings, means for producing flow of air through said casing, a hollow member secured at one end to said casing and extending inwardly from one of said exhaust openings, the other end of said hollow member being arranged to receive all of the air exhausted from said means, said hollow member being formed with a port communicating with the other of said exhaust openings, a sleeve valve reciprocably mounted in said hollow member for closing and opening said port, and an air conduit connectible to said one of said exhaust openings, said sleeve valve being moved to close said port by the connecting of said conduit.

5. In a vacuum cleaner, a casing adapted to be supported on a horizontal surface and having an inlet opening and a plurality of exhaust openings, means for producing flow of air through said casing, one of said exhaust openings being adapted to be connected to an air conduit, valve means operable by the connecting of said conduit to said one of said exhaust openings for cutting off flow of air through the other of said exhaust openings, and means carried by said valve means and disposed across said one of said exhaust openings for deflecting air away from said surface.

6. In a vacuum cleaner, a casing having an inlet opening and a plurality of exhaust openings, means for producing flow of air through said casing, a hollow member secured at one end to said casing and extending inwardly from one of said exhaust openings, the other end of said hollow member being arranged to receive all of the air exhausted from said means, said hollow member being formed with a port communicating with the other of said exhaust openings, a valve member reciprocably mounted in said hollow member for selectively closing and opening said port, and vanes carried by said valve member for deflecting air passing through said one of said exhaust openings.

7. In a vacuum cleaner, a casing adapted to be supported on a horizontal surface and formed with an inlet opening, one end of said casing having a portion inclined to the horizontal and formed with a plurality of exhaust openings therein, means for producing flow of air through said casing, one of said exhaust openings being adapted to receive an air conduit, the remainder of said exhaust openings being located entirely in a portion of said end which is inclined away from said horizontal surface whereby air discharged therethrough is directed upwardly and away from said surface, valve means operative by connection of said air conduit for preventing flow of air through said remainder of said openings, and means for deflecting air discharged through said one of said openings upwardly and away from said surface.

8. In a vacuum cleaner, a casing adapted to be supported on a horizontal surface and formed with an inlet opening, one end of said casing

being rounded and formed with a plurality of exhaust openings therein, means for producing flow of air through said casing, one of said exhaust openings being adapted to receive an air conduit, the remainder of said exhaust openings being located entirely in a portion of said end which is inclined away from said horizontal surface whereby air discharged therethrough is directed upwardly and away from said surface, 5 a valve member reciprocably mounted in said one of said openings and operative by connection of said air conduit to prevent flow of air through said remainder of said openings, and means carried by said valve member for deflecting air discharged through said one of said openings upwardly and away from said surface when said air conduit is disconnected.

9. In a vacuum cleaner, a casing having an air inlet, a fan in said casing for inducing flow 20 of air through said inlet, a hollow member extending inwardly from an exhaust opening formed in said casing, means for conveying all of the air discharged from said fan to said hollow member, said casing being formed with additional exhaust openings and said hollow member being formed with a port communicating with said additional exhaust openings, and valve means for closing said port.

10. In a vacuum cleaner, a casing having an air inlet, a fan in said casing for inducing flow 30 of air through said inlet, a hollow member extending inwardly from an exhaust opening formed in said casing, means for conveying all of the air discharged from said fan to said hollow member, said casing being formed with additional exhaust openings and said hollow member being formed with a port communicating with said additional exhaust openings, an air conduit adapted to be connected to the first mentioned 35 exhaust opening, and valve means operable by connecting said air conduit for closing said port.

11. In a vacuum cleaner, a casing adapted to be supported on a horizontal surface and formed with an air inlet, a fan in said casing for inducing flow of air through said inlet, a hollow member extending inwardly from an exhaust opening formed in said casing, means for conveying all of the air discharged from said fan to said hollow member, said casing being formed with additional exhaust openings so positioned as to direct air flowing therethrough away from said surface, said hollow member being formed with a port communicating with said additional exhaust openings, valve means for selectively closing said port, and means for directing air flowing through the first mentioned exhaust opening away from said surface.

12. In a vacuum cleaner, a casing including a main member and an end-piece for closing one end of said main member, said end-piece forming a part of the exterior of said casing and having an exhaust opening, movable air deflecting means for guiding flow of air through said opening, means within said opening for removably securing said end-piece to said main member, said securing means terminating substantially flush with said deflecting means when the latter is in normal position, said deflecting means being movable by the connecting of said conduit and being movable to render said securing means accessible, and valve means operative by the movement of said deflecting means from normal position for cutting off flow of air through the other of said exhaust openings.

cessible, and means for producing flow of air through said casing and said opening.

13. In a vacuum cleaner, a casing including a main member and an end-piece for closing one end of said main member, said end-piece forming a part of the exterior of said casing and having a plurality of exhaust openings therein, an air conduit adapted to be connected to one of said openings, valve means operable by the connection of said conduit to cut off flow through the remainder of said openings, means disposed within said one of said exhaust openings and within said valve means for securing said end-piece to said main member, and means for circulating air through said casing.

14. In a vacuum cleaner, a casing including a main member and an end-piece for closing one end of said main member, said end-piece forming a part of the exterior of said casing and having a plurality of exhaust openings therein, an air conduit adapted to be connected to one of said openings, air deflecting means for guiding flow of air through one of said openings, valve means operable by the connection of said conduit to cut off flow through the remainder of said openings, means disposed within said one of said exhaust openings and within said valve means and extending through said air deflecting means for securing said end-piece to said main member, and means for circulating air through said casing.

15. In a vacuum cleaner, a casing including a main member and an end-piece for closing one end of said main member, said end-piece forming a part of the exterior of said casing and having an exhaust opening, movable air deflecting means in said opening normally substantially flush with the exterior of said casing for guiding flow of air through said opening, means within said opening for removably securing said end-piece to said main member, said securing means terminating substantially flush with said deflecting means when the latter is in normal position, and an air conduit connectible within said opening, said deflecting means being movable by the connecting of said conduit and being movable to render said securing means accessible.

16. In a vacuum cleaner, a casing including a main member and an end-piece for closing one end of said main member, said end-piece forming a part of the exterior of said casing and having a plurality of exhaust openings, movable air deflecting means in one of said openings and normally substantially flush with the exterior of said casing, means within said one of said openings for removably securing said end-piece to said main member, said securing means terminating substantially flush with said deflecting means when the latter is in normal position, an air conduit connectible to said one of said openings, said deflecting means being movable by the connecting of said conduit and being movable to render said securing means accessible, and valve means operative by the movement of said deflecting means from normal position for cutting off flow of air through the other of said exhaust openings.

GUSTAF EINAR LOFGREN.
